CLAIM

The ornamental design for a cellulite treatment assembly, as shown and described.

DESCRIPTION

FIG. 1 is a rear perspective view of a cellulite treatment assembly showing our new design;
FIG. 2 is a right side view thereof;
FIG. 3 is a left side view thereof;
FIG. 4 is a rear side view thereof;
FIG. 5 is a front side view thereof;
FIG. 6 is a top side view thereof; and,
FIG. 7 is a bottom side view thereof.

The broken lines shown in FIGS. 1-7 illustrate portions of the cellulite treatment assembly that form no part of the claimed design.
